UNITED STATES PATENT OFFICE.

LOUIS E. ENDSLEY, OF PITTSBURGH, PENNSYLVANIA.

BUFFER DEVICE FOR DRAFT GEARS AND THE LIKE.

Application filed March 24, 1925. Serial No. 17,958.

My invention relates to buffer devices for draft gears and the like, and is particularly applicable to those structures wherein spring steel plates are employed as shock absorbing elements.

One object of my invention is to provide means whereby a spring steel plate or plurality of plates are stressed substantially uniformly at all points throughout their length when deflected, as compared to those structures wherein the stress on a plate at the central portion only is maximum and the stresses at points removed from said central portion are reduced from the maximum stress to zero.

Another object of my invention is to increase and improve generally the absorbing capacity of a given number of spring plates.

One manner in which my invention may be practiced is shown in the accompanying drawing wherein Fig. 1 is a sectional view showing a general arrangement of draft gear rigging for railway cars in which my invention is incorporated, and Fig. 2 is a view, on an enlarged scale, of a portion of the apparatus of Fig. 1 and illustrating my invention diagrammatically.

Heretofore it has been customary, in employing spring steel plates as shock absorbing members, to cause deflection thereof upon a surface that is uniformly curved or that has a single radius. The objection to this arrangement arises from the fact that the spring plates are subjected to very great stresses at the point where deflection begins, and to comparatively little stress at points removed therefrom. For instance, if a spring plate or a plurality of plates are placed upon a surface having uniform curvature and the ends of the plates deflected until they contact with such surfaces throughout their length, the plates at their mid portions may be under a stress of 120,000 lbs.; at given points on either side of said first-named point the stresses may be but 115,000 lbs.; at points still farther removed, the stresses may be 90,000 lbs.; still farther away the plates may be under a stress of but 70,000 lbs., while at the extreme ends of the curved plates their stresses will be zero.

By providing, for the spring plates, a seating surface having an initial curvature of a given radius and changing the curvature of said surface at points removed from the initial point so that a plurality of curves of progressively smaller radii are provided,

I am enabled to effect a substantially uniform stress on the spring plates at all points throughout their length. Thus, by this arrangement, the plates in the first zone of deflection may be under a stress of 114,000 lbs., in the second zone (at each side of the first zone) they may be under a stress of 114,000 lbs., and also under stresses of 114,000 lbs. in the third and fourth zones, as compared to the stresses enumerated above in connection with the former types of buffers. Thus there is a uniform stress to substantially the end of the plates.

In the drawing I have shown a draft sill or beam 3 provided with follower stops 4 and 5. A yoke 6 of the usual form may be employed. A plurality of sets of spring steel plates 7 are also provided. The plates 7 are mounted between a rear follower 8 and a front follower 9, and spacers 10 and 11 are interposed between the groups of plates 7.

The spacing plates 10 are concave so that only their end portions will engage with the spring plates 7, even during deflection thereof. The end group of plates are deflected about the curved surfaces of the follower plates 8 and 9, and the two intermediate groups of plates are deflected about the curved faces of the convex spacer block 11.

The curvatures of the plate-contacting surfaces of the blocks 8, 9 and 11 are preferably the same, so that a description of the curvature of the follower block 8 will suffice also for blocks 9 and 11.

In Fig. 2 I have shown only one-half of the follower 8, since the curvature at each side of its central portion is the same. The radius of curvature of the follower 8 in the zone marked *a* is such that when the plates 7 are bent into contact with the follower throughout the distance *a*, they are under maximum stress. Within the zone *b* the follower 8 has a curve of less radius than that of zone *a*. Therefore, further deflection of the plates 7 is required in order to bring them into engagement with that portion of the follower 8 lying within zone *b*. That portion of the plates overlying zone *b* is likewise under maximum stress (114,000 lbs., for example). The follower 8 has a curvature of still shorter radius within the zone *c*, and likewise with respect to zone *d*. The dotted line 12 indicates a true arc struck from the radius of the mid-portion of the follower 8.

I thus provide a plurality of seating sur-

faces on blocks 8, 9 and 11, respectively, which have curvatures of successively shorter radii, and thereby utilize the yielding capacity of the spring plates to their fullest extent, as compared to the older structures, wherein a single curved surface of uniform arcuate shape is employed, and wherein the plates are under maximum stress at their mid-portions. The seating surface could obviously be of elliptical form, if desired.

Below is a table of actual tests made, under similar conditions, with a follower block of the usual uniform radius and my special form of block having non-uniform radii. The readings were obtained by a strain gage of a well known type, and show that as deflection of the spring plates increased against the surface of the standard type of follower there was a very rapid decrease in stress, as compared to the almost uniform stress in the case of my follower, up until the three-inch mark.

25   *Maximum stresses in plates.*

30	Location on plate	27½" radius Std. follower	Follower having radii decreasing from 29" to 17"
	Center	Stress.	Stress.
	1½" off center	130,000 lbs.	120,000 lbs.
	3" off center	124,000	120,000
	4½" off center	94,000	118,000
		50,000	96,000

35   Both plates were 11¾" long.

It will be apparent that my invention contemplates broadly the provision of a bearing surface of such form that portions 40 of the spring plates removed from the initial point of deflection are successively placed under stresses greater than would be the case when employed against a surface having uniform curvature, and that I do not limit myself to certain degrees of curvature nor to the number of zones of deflection.

I claim as my invention:

1. In draft gear structures, a pair of spaced follower blocks having seating surfaces, spring steel plates disposed between said surfaces, and a double concave spacer between said plates, each of said surfaces having a curvature of a given radius at its normal point of contact with one of said plates and having a curvature of shorter radius at points removed from said normal point.

60   2. In draft gear structures, a pair of spaced follower blocks having seating surfaces, spring steel plates disposed between said surfaces, and a double concave spacer between said plates, each of said surfaces having a curvature of a given radius at its normal point of contact with one of said

plates, and having curvatures of progressively shorter radii at points successively removed from said normal point. 65

3. In draft gear structures, a pair of spaced follower blocks having seating surfaces, spring steel plates disposed between 70 said surfaces, and a double concave spacer between said plates, each of said surfaces having a curvature of a given radius at its normal point of contact with one of said plates, and having curvatures of progressively 75 shorter radii to either side of said normal point, at points successively removed therefrom.

4. Buffer structure comprising a seating block, a spring steel plate normally engaging said block at one portion of its surface, and impact receiving means for deflecting said plate into engagement with another portion of said surface, the first named portion being formed to cause that part of the spring adjacent thereto to assume one curvature, and the second named portion being formed to cause that part of the spring engaging therewith to assume a curvature having a different radius than the curvature of 90 the first-named portion. 90

5. Buffer structure comprising a curved seating block, a spring plate normally engaging said block at its mid-portion, and impact receiving means for deflecting said plate into engagement with portions of said block to either side of said mid-portion, the last-named portions of said block being curved about radii of different length than the radius of said mid-portion. 95

6. Buffer structure comprising a curved seating block, a spring plate normally engaging said block at its mid portion, and impact receiving means for deflecting said plate into engagement with a plurality of portions at each side of said mid-portion, the engaging surfaces of said plurality of portions having curvatures of progressively shorter radii at points successively removed from said mid-portions. 105

7. The combination with a spring metal plate, of a seat therefor having a curvature of generally arcuate form but of varying radii, and an impact receiving member for deflecting said plate against said seat. 115

8. The combination with a spring metal plate and a support therefor, of a force-transmitting member having engagement with said plate at a point removed from the said support, and means limiting the bending movement of said plate but permitting increased bending movements thereof at points successively removed from said support. 120

In testimony whereof I, the said LOUIS E. ENDSLEY, have hereunto set my hand. 125

LOUIS E. ENDSLEY.
